UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

TWO-HOLE SEW-ON BUTTON.

Application filed November 16, 1925. Serial No. 69,320.

To all whom it may concern:

Be it known that I, FRANKLIN R. WHITE, a citizen of the United States of America, residing at Waterbury, in the county of 5 New Haven and State of Connecticut, have invented certain new and useful Improvements in Two-Hole Sew-On Buttons, of which the following is a specification.

My invention relates to new and useful 10 improvements in two hole buttons of the sew-on type, and has for an object to so construct a button that it may be placed in an automatic button sewing machine and guided in its movement to the needle or 15 needles for the purpose of attachment.

The present application is a companion 20 one of four others filed by me of even date herewith bearing Serial Numbers 69,318, 69,319, 69,321, and 69,322.

One of the objects of the present invention 25 is to provide a button wherein the hub has rounded ends and parallel sides while the holes for the thread are arranged in certain relation to said parallel sides, as these parallel sides are adapted to be engaged in a track, trough or chute, so that the buttons will be properly fed beneath the needle or needles.

Still another object of the invention is to 30 provide a button which can be guided and controlled in its movement to its needle or needles and be prevented from swerving so the holes will register with the needles when the button reaches its final position beneath the said needle.

As is well known to those skilled in the 35 art of button attaching machines, heretofore it has been necessary to use some very complicated form of mechanism for correctly centering the button below the needles.

With the present invention, however, the 40 construction of the button is such that the buttons cooperate with a much more simple form of guide mechanism and are carefully and correctly guided and controlled to their 45 position beneath the needle.

With the above and other objects in view, 50 the invention consists in certain new and novel arrangements as will be hereinafter more fully described and pointed out in the 55 claims.

Referring now to the drawings showing a preferred and a slightly modified form of the invention,

Fig. 1 is a top plan view, the dotted lines

showing the outline of the lower surface 55 of the hub.

Fig. 2 is a sectional view taken on line 2-2 of Fig. 1.

Fig. 3 is a view from the undersurface of 60 the button.

Fig. 4 is a view similar to Fig. 1, but showing a slightly modified form.

Fig. 5 is a sectional view taken on line 5-5 of Fig. 4, and

Fig. 6 is a view from the bottom of the 65 button.

Referring now more in detail to the preferred form, I have shown a button formed of wood, metal, bone or other suitable material comprising a body portion 1 which is 70 slightly depressed at its center 2, has the outstanding rim 3, and the hub 4 on its undersurface. This hub 4, in the early formation of the button may be circular in outline, but is then cut away at its sides so that 75 these two sides 5 extend parallel to each other, and in reality form a projection that is adapted to fit within a slot or guideway (not shown) of a chute in an automatic button sewing machine. The ends 6 of the hub 80 are arcuate as may be clearly seen in Figs. 1 and 3, both of these arcs being struck from a common center, or in other words, the center of the lower surface of the hub.

The hub is further provided with two 85 holes or openings 7 through which the needles will pass and these holes or openings are so located that if a line be drawn across the hub from end to end, and through the center point on the surface on the hub, it 90 will coincide with the centers about which the two holes are constructed.

With the buttons formed in this manner, 95 they may be placed in a button attaching machine (not shown) and the parallel sides or walls formed in the hub will properly guide and control the button during its movement to the needle or needles.

Referring now to Fig. 4, I have shown a 100 similar button comprising a body portion 8 having the depressed center 9, the rim 10 and the depending hub 11. Likewise the hub is cut to form the two parallel side walls 12 and two holes 13 are provided, but in this instance the holes are arranged in 105 a different position. The purpose of arranging these in a different position is that the needles in the machine may be arranged

in a horizontal manner with respect to the hub of the button, rather than in a lengthwise direction, and therefore, in this instance, I have shown the two holes 13 located adjacent the respective side walls 12 diametrically opposite each other, so that, if a line is drawn through their center, it will pass through the central point 14 of the hub.

10 The contour of the two ends of the hub is formed by striking two arcs with the point 14 as a center.

From the foregoing it will be seen that I have constructed a button which is exceedingly cheap to manufacture, and where-in the side walls of the hub are constructed so that they may cooperate with a track or chute (not shown) of an automatic button sewing machine, to guide and control the 20 button in its movement to the needle.

By having the ends of the hub rounded, the button may pass into the chute if it is facing in one of two directions. The shape of the body and the shape of the rim are 25 not important, the gist of the invention being the rounded ends of the hub, the parallel sides and the respective positions of the holes.

Other slight changes might be made without in any way departing from the spirit 30 and scope of the invention.

Having thus described the same, what I claim as new and desire to secure by Letters Patent is:—

35 1. A two-hole sew-on button comprising a body portion, a hub, said hub having parallel side walls and rounded ends, the said hub provided with two holes each located equidistant from the central point on the 40 hub surface, and the side walls adapted to

guide the movement of the button in a button sewing machine.

2. A two-hole sew-on button comprising a body portion, a depending hub, said hub being rounded at its opposite ends and having side walls parallel with each other merging with the rounded ends, the said hub provided with two holes each of which is equidistant from the said two parallel side walls, and the side walls adapted to guide the button when fed in a button attaching machine. 45

3. A two-hole sew-on button comprising a body portion, a depending hub, the said hub being arcuate at its opposite ends and having a portion cut away at each side of the hub to form two parallel side walls merging respectively with the arcuate ends, the said hub provided with two holes extending therethrough and said holes being diametrically opposite to each other and respectively adjacent the said side walls, the side walls adapted to guide and control the movement of the button when used in a button attaching machine. 55

4. A two-hole sew-on button comprising a body portion, an outwardly extending rim, the said body portion being depressed at its center and having a downwardly extending hub, said hub provided with two openings therein and the said hub being rounded at its ends and having parallel side walls merging with said ends, and the said holes diametrically opposite each other and equidistant from the said side walls, the said side walls adapted to control the movement when the button is used in a button attaching machine. 60 65

In testimony whereof I affix my signature.

FRANKLIN R. WHITE.
